APPROACH ROUTE CONTROL APPARATUS, INCLUDING TRAIN CARRIED CONTROL MEANS FOR RAILWAY TRACK SWITCHES AND ASSOCIATED SIGNALS

Chi Chang Chu, Pittsburgh, Pa., assignor to Westinghouse Air Brake Company, a corporation of Pennsylvania

Application May 23, 1950, Serial No. 163,742

8 Claims. (Cl. 246—219)

1

My invention relates to approach route control apparatus for railway track switches and associated signals such, for example, as in an interlocking plant. More specifically, my invention relates to an arrangement embodying train identification means such, for example, as manually operable means carried on an approaching train or other railway vehicle for effecting operation of railway track switches and associated signals for preparing a traffic route according to a corresponding condition of such train identification means while the train or other railway vehicle on which it is carried occupies a given portion of track adjacent the railway track switches and associated signals.

It is common practice on railroads for a train which is to enter or leave a main track at a siding switch to stop while a trainman goes on ahead and operates the switch. This results in loss of time and energy, and sometimes results in damage to equipment, by stopping and starting, especially in the case of a heavy freight train.

Such losses and damage can be prevented if the track switches and associated signals are operated by power means controlled manually from a remote point such, for example, as a dispatcher's office, through the medium of centralized traffic control apparatus, or from an interlocking tower or station through the medium of levers in an interlocking machine. Various arrangements have also been provided for effecting operation of isolated railway track switches to the reverse position, without stopping the train, by manually operable means carried on the engine of an approaching train. Such arrangements have embodied trackway inductor means cooperating with train-carried inductor means, trackway sound responsive means controlled by whistle sounds, trackway means responsive to blasts of air from the passing train, trackway light responsive means, timing means, and trackway ramps or contact rails.

An object of my invention is the provision of novel and improved means for effecting operation of railway track switches and associated signals from an approaching train, for preparing various traffic routes without stopping the train, under certain conditions such, for example, as where there is no centralized control system or where the traffic over a group of switches is such that it is not considered to require the continuous services of a leverman in an interlocking plant.

Features of my invention for attaining this object are a wayside oscillator which becomes energized in response to the presence of a train on an approach section of track adjacent the switch, such as in an interlocking plant; train-carried receiving means which becomes operated by energy transmitted from the wayside oscillator; and a train-carried oscillator con-

2

trolled by the train-carried receiving means and by train-carried identification means for supplying energy to the track rails for effecting energization of wayside receiving means which in turn may effect operation of one or more railway track switches and associated signals for preparing one or another corresponding railway traffic route.

Advantages of such an arrangement over previous arrangements for effecting operation of a railway track switch by manually operable means carried on an approaching train are that it does not require trackway apparatus such, for example, as inductors or contact elements, located close to the track, which are subject to damage by trains, and it does not employ timing means which requires a train to occupy track sections at specific times in order to effect operation of a railway track switch.

Another feature of my invention is that, when a given route has been prepared by means associated with a given train, an indication is displayed for giving corresponding information to the trainmen of a second train which is following the given train. The second train can, therefore, follow the preceding given train closely if the second train is to take the same route as the preceding train, or if the second train is to take a different route, it can stop on a given approach section and wait until the preceding train has moved off of a portion of the given route, and a different indication will then be displayed for informing the operator of the following train that the route he is to take is being prepared.

I shall describe one form of apparatus embodying my invention, and shall then point out the novel features thereof in claims.

The accompanying drawings, Figs. 1a and 1b, when placed end to end, with Fig. 1a on the left, 40 constitute a diagrammatic view showing one form of apparatus embodying my invention, in which railway vehicle carried apparatus includes a receiver which is inductively controllable by current of a first given character in the rails of a track which is occupied by a vehicle on which the apparatus is carried; in which the vehicle carried apparatus also includes an oscillator which supplies current inductively to the track rails, of a second or a third given character according to the position of a manually operable control device also carried on the railway vehicle; in which current of the first given character is supplied to the rails of an approach section of railway track by a wayside oscillator; in which a wayside receiver is selectively responsive to current of the second or third given character in the rails of the approach section for controlling a first or a second primary route control relay, respectively; in which a third and a fourth route control relay, which I shall call intermediate

route control relays, are controlled in part by the first and second route control relays; in which a fifth and a sixth route control relay which are also called final route control relays are controlled in part by the third and fourth route control relays, respectively; in which a home signal is provided which is capable of displaying a first or a second proceed indication according as one or another railway traffic route is prepared; in which a distant signal is provided for the home signal; and in which route indicators adjacent the distant signal are controlled according to the route which has been prepared.

Similar reference characters refer to similar parts in the drawings.

Referring further to the drawings, a stretch of railway track is shown including a switch, designated by the reference character 3W, in Fig. 1b, which is operable to a first or a second extreme position in the preparation of various routes such, for example, as in an interlocking plant. Two such routes are shown in the drawings. Switch 3W is movable between its first and second extreme positions by any suitable power operated mechanism designated by the reference character 3WM such, for example, as the well-known electropneumatic type, or the electric motor type.

A home signal, designated by the reference character 4S, for governing traffic movements over the different routes, has an upper arm, designated by the reference character 4a, which becomes operated for directing traffic movements over a railway traffic route which includes switch 3W in the position in which it is shown in the drawing, which I shall call the first or normal extreme position. Signal 4S has also a lower arm, designated by the reference character 4b, which becomes operated for directing traffic movements over a railway traffic route which includes switch 3W in the opposite position, which I shall call the second or reverse extreme position.

At the opposite or leaving ends of the two routes shown, over which signal 4S governs traffic movements, are signals 5S and 6S, which may be automatic signals, for governing traffic movements in the same direction as signal 4S, toward the right, as shown in the drawing, which I shall assume is the eastbound direction.

A distant signal 2S, shown in Fig. 1a, governs eastbound traffic movements approaching signal 4S.

A signal 1S to the rear of signal 2S governs eastbound traffic movements approaching signal 2S.

Each of the signals 1S, 2S, 4S, 5S and 6S may be of any suitable design such, for example, as the well-known color light type having a clear proceed lamp G, a caution proceed lamp Y, and a stop lamp R, as shown for signals 1S and 2S, and for each of the two arms of signal 4S.

Route indicators, designated by the reference characters NK and RK, are located adjacent signal 2S. As shown in the drawings, these route indicators are mounted on the same mast as signal 2S.

The stretch of railway track shown in the drawings is divided by insulated joints 7 into section 1T between signals 1S and 2S, which I shall call an approach section, section 2T between signals 2S and 4S, which I shall call a detector section, section 3T in which switch 3W is located, which I shall also call a detector section, sections 4aT and 4bT between section 3T and signals 5S and 6S, respectively, which I shall

call route sections, and sections 5T and 6T, which I shall call signal sections. Each track section is provided with a track circuit including a suitable source of current, such as a battery 8, connected across the rails adjacent one end of the section, and a track relay, designated by the reference character R preceded by the reference character for the associated section, connected across the rails adjacent the opposite end of the section. An impedance 92 is connected in series with the battery 8 across the rails of section 1T in order to prevent short circuiting the current from the oscillators through battery 8.

A train, or other railway vehicle, designated by the reference character V, is represented by a pair of wheels 9 and an axle 10, and is shown on a preliminary portion, designated by the reference character OT, of the track, to the rear of signal 1S.

Receiving means carried on vehicle V comprises receiving coils, designated by the reference characters 1e and 2e, which are energizable by current of a first given character such, for example, as a first given frequency, in the track rails, to which receiving apparatus, designated by the reference character VRec on vehicle V, is arranged to respond for energizing an approach route relay, designated by the reference character AUR.

An approach route stick relay, designated by the reference character AUSR, has a pickup circuit controlled by relay AUR, and a stick circuit controlled by a manually operable control device, designated by the reference character P, which is carried on vehicle V.

As shown in the drawings, the device P is a circuit controller of the push-turn type having two normally open push contacts 47 and 53, a normal turn contact, designated by the reference character n, and a reverse turn contact, designated by the reference character r.

A whistle control valve magnet, designated by the reference character XL, carried on the vehicle, is controlled by relays AUR and AUSR, and is made slow releasing by a resistor t and a condenser c connected in series with each other across its winding. A whistle, designated by the reference character X, becomes sounded when the valve magnet XL becomes deenergized for more than a brief release period of time.

A suitable source of current such, for example, as a battery designated by the reference character VQ, having a positive terminal VB and a negative terminal VN, is carried on vehicle V.

Another suitable source of current such, for example, as a battery Q having a positive terminal B and a negative terminal N, is located adjacent the track.

Transmitting means, carried on vehicle V, comprises an oscillator designated by the reference character VOsc which is controlled by relays AUSR and AUR and by circuit controller P for supplying transmitting coils, designated by the reference characters 1i and 2i, with energizing current of a second or a third given character such, for example, as a second or a third given frequency according as control device P is in its n or its r position, respectively. Coils 1i and 2i in turn induce current of corresponding character in the rails of the track which is occupied by vehicle V.

Wayside transmitting means comprises an oscillator, designated by the reference character TOsc, which is connected across the rails of section 1T adjacent signal 2S for supplying current

of a first given character to which the vehicle carried receiver VRec is responsive for energizing relay AUR when vehicle V occupies section 1T.

Wayside receiving means comprises receiving apparatus, designated by the reference character TRec, which is also connected across the rails of section 1T adjacent signal 2S and is responsive to current of the second and third given characters in the rails of section 1T for energizing a first or a second primary route control relay, designated by the reference characters NUR and RUR, respectively.

A third and a fourth route control relay, designated by the reference characters 2NR and 2RR respectively, which I shall call intermediate route control relays, are controlled in part by the primary route control relays.

A fifth and a sixth route control relay, designated by the reference characters 3NR and 3RR, respectively, which I shall call final route control relays, are in turn controlled in part by the intermediate route control relays.

A polarized route control relay, designated by the reference character 3NRWR, which, upon becoming deenergized, retains its contacts closed in the last energized position, is controlled by relays 3NR and 3RR.

A polarized switch control relay, designated by the reference character 3WR, which, upon becoming deenergized, retains its contacts closed in the last energized position, is controlled in part by relay 3NRWR.

A track repeater stick relay, designated by the reference character 3TPSR, is controlled by track relay 3TR and by relays 3NR and 3RR.

Normal and reverse switch indication relays, designated by the reference characters 3NWCR and 3RWCR, respectively, are controlled by polar contacts of relay 3WR and by a switch contact, designated by the reference character 12, which is operated in conjunction with switch 3W and is arranged to be closed in a first or a second position according as switch 3W is operated to its first or second extreme position, respectively.

Each of the signals 1S and 2S, and each arm of signal 4S is shown controlled by a polarized signal relay of the retained neutral type, in which the neutral contacts are slow to pick up and slow to release. Each of the polarized signal relays is designated by the reference character HDR preceded by the numeral in the reference character for the associated signal.

A slow release approach lighting relay, designated by the reference character 2AER, for signal 2S, is controlled in series with relay 1HDR for signal 1S.

An approach repeater relay, designated by the reference character 2AEPR, is controlled by relay 2AER and by relays 2NR and 2RR. Relay 2AEPR is made slow releasing by a resistor *t* and a condenser *c* connected in series with each other across the winding of relay 2AEPR.

An approach stick relay, designated by the reference character 2AESR, is controlled by relays 2AER, 2HDR, 2NR and 2RR.

Having described, in general, the arrangement and the control of the various parts of apparatus embodying my invention, I shall now describe the circuits and operation in detail.

As shown in the drawings, all parts of the apparatus are in the normal condition, that is, the track sections are unoccupied, and therefore all track relays are energized; each of the arms 4a and 4b of signal 4S is displaying the red or stop

indication; signal 2S is unlighted but its control relay 2HDR is energized by current of reverse polarity for controlling signal 2S to display the yellow or caution proceed indication; signal 1S is displaying the green or clear proceed indication; switch 3W is in its first extreme, or normal, position for preparing the route between signals 4S and 5S; the vehicle-carried and the wayside oscillators and receivers are all deenergized; the vehicle-carried circuit controller P is in its normal condition in which its front contacts 47 and 53 and its reverse contact *r* are open and its normal contact *n* is closed; relays 1HDR and 3WR are energized by current of normal polarity; relay 2HDR is energized by current of reverse polarity; relays 2AER, 2AEPR and 3NWCR and whistle valve magnet XL are energized; and relays AUR, AUSR, NUR, RUR, 2NR, 2RR, 2AESR, 3NR, 3RR, 3NRWR, 3TPSR, 3RWCR, 4aHDR and 4bHDR are deenergized.

The circuit by which relay 3NWCR is energized passes from terminal B, through contact 11 of relay 3WR closed in the normal position, contact 12 of switch 3W closed in the first extreme or normal position, and the winding of relay 3NWCR to terminal N.

The circuit by which relay 3WR is energized by current of normal polarity passes from terminal B, through contact 13 of relay 4bHDR, contact 14 of relay 3TR, contact 15 of relay 3NRWR closed in the normal position, winding of relay 3WR, contact 16 of relay 3NRWR closed in the normal position, and contact 17 of relay 4aHDR to terminal N.

The circuit by which relay 2HDR is energized by current of reverse polarity passes from terminal B, through contact 18 of relay 3TR, back point of contact 19 of relay 4aHDR, back point of contact 20 of relay 4bHDR, contact 21 of relay 2TR, winding of relay 2HDR, back point of contact 22 of relay 4bHDR, and the back point of contact 23 of relay 4aHDR to terminal N.

The circuit by which relays 1HDR and 2AER are energized by current of normal polarity passes from terminal B, through the winding of relay 2AER, contact 24 of relay 2TR, front point of contact 25 of relay 2HDR, contact 26 of relay 1TR, winding of relay 1HDR, and the front point of contact 27 of relay 2HDR to terminal N.

The circuit by which relay 2AEPR is energized passes from terminal B, through the front point of contact 28 of relay 2AER, and the winding of relay 2AEPR in multiple with a series connection through resistor *t* and condenser *c*, to terminal N.

The circuit by which green lamp G of signal 1S is lighted passes from terminal B, through the front point of contact 31 of relay 1HDR, contact 32 of relay 1HDR closed in the normal position, and lamp G of signal 1S to terminal N. The red lamp of arm 4a of signal 4S is energized by a circuit passing from terminal B, through the back point of contact 33 of relay 4aHDR, and lamp R of arm 4a to terminal N. Red lamp R of arm 4b of signal 4S is energized by a circuit which is similar to the circuit just traced for lamp R of arm 4a.

The whistle control valve magnet XL of vehicle V, shown in Fig. 1a, is energized by a circuit passing from terminal VB, through contact 49 of relay AUSR, and the winding of magnet XL in multiple with a circuit path through a resistor *t* and a condenser *c* to terminal VN.

I shall assume that, with apparatus embodying my invention arranged as shown in the ac-

companying drawings, a trainman or other operator on vehicle V moves the circuit controller P to the pushed-in position, thereby closing contacts 47 and 53, and leaves the circuit controller in the normal turn position in which contact n remains closed.

I shall assume further that the vehicle operator then drives vehicle V onto approach section 1T, causing track relay 1TR to become deenergized. Contact 26 of relay 1TR then opens the circuit previously traced for relay 1HDR, causing relay 1HDR to become deenergized. Contact 31 of relay 1HDR then opens the circuit previously traced for lamp G of signal 1S, and closes a circuit for lighting lamp R of signal 1S, passing from terminal B, through the back point of contact 31 of relay 1HDR, and lamp R of signal 1S to terminal N.

Relay 2AER, which is in series with relay 1HDR, also becomes deenergized by the opening of contact 26 of relay 1TR. Upon the lapse of a brief interval of time, contact 28 of relay 2AER opens at its front point, thereby deenergizing relay 2AEPR.

Contact 28 of relay 2AER, upon becoming closed at its back point, completes a circuit for lighting lamp Y of signal 2S, this circuit passing from terminal B, through the back point of contact 28 of relay 2AER, front point of contact 37 of relay 2HDR, contact 38 of relay 2HDR closed in the reverse position, and lamp Y of signal 2S, to terminal N.

Upon the closing of contact 42 of relay 2AER, relay 2AESR becomes energized by a pickup circuit passing from terminal B, through contact 39 of relay 2NR, contact 40 of relay 2RR, the winding of relay 2AESR, contact 42 of relay 2AER, and the front point of contact 43 of relay 2HDR to terminal N. Relay 2AESR then completes its own stick circuit, which is the same as the pickup circuit just traced except that it includes contact 41 of relay 2AESR instead of contacts 39 and 40 of relays 2NR and 2RR, respectively.

Upon the closing of contact 45 of relay 2AER, the wayside oscillator TOsc becomes energized by a circuit passing from terminal B, through contact 44 of relay 2AEPR, contact 45 of relay 2AER, and oscillator TOsc to terminal N. Oscillator TOsc therefore now supplies current of a first given character to the rails of section 1T.

Such current in the rails of section 1T inductively energizes the receiving coils 1e and 2e carried on vehicle V for in turn energizing the vehicle-carried receiving means including the receiving apparatus VRec which in turn energizes approach route relay AUR. The pickup circuit for relay AUSR then becomes closed, passing from terminal VB, through contact 46 of relay AUR, and the winding of relay AUSR to terminal VN. Relay AUSR thereupon completes its own stick circuit passing from terminal VB, through contact 47 of controller P, contact 48 of relay AUSR, and the winding of relay AUSR to terminal VN.

When relay AUSR becomes energized, contact 49 opens the circuit previously traced for whistle control valve magnet XL. A second circuit is, however, now completed for energizing valve magnet XL, this circuit passing from terminal VB, through contact 50 of relay AUR, and the winding of magnet XL in multiple with resistor t and condenser c to terminal VN.

Upon the lapse of a brief period of time after relay 2AEPR becomes deenergized by the opening of contact 28 of relay 2AER at its front point,

5 contact 44 of relay 2AEPR opens the circuit previously traced for the wayside oscillator TOsc, thereby discontinuing energization of the rails of section 1T by current of the first given character or frequency. The vehicle-carried receiver VRec and the relay AUR therefore become deenergized. Contact 50 of relay AUR therefore opens the second circuit traced for whistle valve magnet XL. Relay AUR will remain deenergized for only a short period, however, until relay 2AEPR becomes energized again, because of energization of relay 2NR, which will be traced presently, and since the whistle magnet XL is slow releasing, whistle X will not be sounded during this brief period.

Relay AUR, upon becoming deenergized, completes a circuit for energizing vehicle-carried oscillator VOsc, this circuit passing from terminal VB, through contact 51 of relay AUSR, contact 52 of relay AUR, contact 53 of controller P, contact n of controller P, and the vehicle-carried oscillator VOsc, to terminal VN. Transmitting coils 1i and 2i will therefore now be energized by oscillator VOsc for inducing current of the second given character or frequency in the rails of track section 1T.

The wayside receiver TRec will respond to current of the second given character for energizing the first primary route control relay NUR. Relay 30 NUR, upon becoming energized, completes a circuit for energizing the third route control relay 2NR, this circuit passing from terminal B, through the back point of contact 54 of relay RUR, contact 55 of relay NUR, winding of relay 35 2NR, contact 57 of relay 2RR, and contact 58 of relay 2AESR to terminal N. Relay 2NR then completes its own stick circuit, which is the same as the pickup circuit just traced except that it includes contact 56 of relay 2NR instead of the back point of contact 54 of relay RUR, and contact 55 of relay NUR. Relay 2NR, upon becoming energized, completes a second circuit for energizing relay 2AEPR, this circuit passing from terminal B, through contact 29 of relay 2NR, and the winding of relay 2AEPR in multiple with resistor t and condenser c, to terminal N.

The wayside oscillator TOsc therefore now again becomes energized, by its circuit previously traced, for supplying current of the first given character to the rails of track section 1T. The vehicle-carried receiver VRec responds to this current of the first given character for again energizing relay AUR, which in turn opens the circuit traced for energizing the vehicle-carried oscillator VOsc and again completes the second circuit traced for valve magnet XL.

60 Relay 2NR, upon becoming energized, also completes a circuit for energizing route indicator NK, this circuit passing from terminal B, through contact 59 of relay 2NR, and route indicator NK to terminal N.

With relay 2NR energized, the fifth or final route control relay 3NR is energized by a circuit passing from terminal B, through contact 60 of relay 2HDR, front point of contact 61 of relay 2NR, contact 62 of relay 2RR, winding of relay 3NR, and contact 63 of relay 3RR to terminal N. Relay 3NR, upon becoming energized, completes a circuit for energizing relay 3NRWR by current of normal polarity, this circuit passing from terminal B, through the back point of contact 64 of relay 3RR, contact 65 of relay 3NR, and the right-hand portion of the winding of relay 3NRWR to terminal N. Since contacts 15 and 16 of relay 3NRWR are already closed in the nor-

mal position, there will be no change in the position of these contacts. Therefore, relay 3WR will remain energized by current of normal polarity in the circuit previously traced.

Relay 3NR, upon becoming energized, however, completes a pickup circuit for energizing relay 3TPSR, this circuit passing from terminal B, through contact 67 of relay 3NR, contact 70 of relay 3TR, and the winding of relay 3TPSR to terminal N. Relay 3TPSR then completes its own stick circuit passing from terminal B, through contact 69 of relay 3TPSR, contact 70 of relay 3TR, and the winding of relay 3TPSR to terminal N.

Relay 3TPSR, upon becoming energized, completes a circuit for energizing relay 4aHDR by current of normal polarity, this circuit passing from terminal B, through the front point of contact 71 of relay 5TR, contact 72 of relay 3TPSR, contact 73 of relay 4bHDR, the winding of relay 4aHDR, contact 74 of relay 3NWCR, contact 75 of relay 3TR, contact 76 of relay 4aTR, and the front point of contact 77 of relay 5TR, to terminal N. With relay 4aHDR thus energized by current of normal polarity, the red lamp R of the arm 4a of signal 4S will be extinguished, and green lamp G will become lighted by a circuit passing from terminal B, through the front point of contact 33 of relay 4aHDR, contact 34 of relay 4aHDR closed in the normal position, and lamp G of arm 4a of signal 4S to terminal N. Relay 4aHDR, upon becoming energized, opens its contact 17, thereby deenergizing relay 3WR. When relay 3WR becomes deenergized, its contacts remain closed in the position to which they were last operated and therefore relay 3NWCR remains energized.

With relay 4aHDR energized, relay 2HDR will become energized by current of normal polarity in a circuit passing from terminal B, through contact 18 of relay 3TR, front point of contact 23 of relay 4aHDR, back point of contact 22 of relay 4bHDR, the winding of relay 2HDR, contact 21 of relay 2TR, back point of contact 20 of relay 4bHDR, and the front point of contact 19 of relay 4aHDR, to terminal N. With relay 2HDR thus energized by current of normal polarity, yellow lamp Y of signal 2S will become extinguished, and green lamp G of this signal will be lighted by a circuit passing from terminal B, through the back point of contact 28 of relay 2AER, front point of contact 37 of relay 2HDR, contact 38 of relay 2HDR closed in the normal position, and lamp G of signal 2S to terminal N.

With route indicator NK energized and signal 2S displaying the clear proceed indication, the operator of vehicle V will know that switch 3W is in its normal position and that signal arm 4a of signal 4S is displaying a proceed indication. The operator of vehicle V can therefore drive vehicle V past signal 2S at normal speed.

When vehicle V enters section 2T, relay 2TR becomes deenergized, and therefore its contact 21 becomes opened, causing relay 2HDR to be deenergized. Relay 2HDR, upon becoming deenergized, opens the circuit previously traced for green lamp G of signal 2S, and completes the circuit for red lamp R of this signal, passing from terminal B, through the back point of contact 28 of relay 2AER, back point of contact 37 of relay 2HDR, and lamp R of signal 2S to terminal N.

Relay 2HDR, upon becoming deenergized, causes relay 2AESR to in turn become deenergized, because of the opening of contact 43 of relay 2HDR at its front point. A second stick

circuit is now completed for relay 2NR, which is the same as the stick circuit previously traced for this relay except that it includes the back point of contact 43 of relay 2HDR instead of contact 58 of relay 2AESR. The first stick circuit for relay 2NR is now open at contact 58 of relay 2AESR. Relay 2NR will, however, be retained in the energized condition by the second stick circuit, so that the route indicator NK will remain energized. Relay 3NR will, however, become deenergized on account of contact 60 of relay 2HDR now being open. Relay 3NRWR will then also become deenergized by the opening of contact 65 of relay 3NR.

When the vehicle-carried receiving coils 1e and 2e have passed the insulated joints 7 at signal 2S, the vehicle-carried receiver VRec will be deenergized. With relay AUR thereby also deenergized, and with relay AUSR still energized by its stick circuit, if the operator of vehicle V has not already restored control device P to its pulled-out position, the whistle control valve magnet XL will be deenergized, causing whistle X to be sounded. The operator of vehicle V will therefore now pull control device P out to its normal position, thereby opening its contacts 47 and 53 and deenergizing relay AUSR and the vehicle-carried oscillator VOsc. With relay AUSR deenergized, the circuit first traced for whistle control valve magnet XL will again be closed, and therefore magnet XL will discontinue the sounding of whistle X. The operator of vehicle V could, however, have restored controller P to its normal position as soon as route indicator NK became energized, because relay 2NR will be retained in its energized condition by its stick circuit after having become energized by relay NUR having completed a pickup circuit for relay 2NR.

When vehicle V leaves section 1T, relay 1HDR will become energized by current of reverse polarity in a circuit passing from terminal B, through the winding of relay 2AER, back point of contact 21 of relay 2HDR, winding of relay 1HDR, contact 26 of relay 1TR, and the back point of contact 25 of relay 2HDR to terminal N. Relay 2AER, on account of being included in series with relay 1HDR, will also be energized, thereupon opening its contact 45 and deenergizing the wayside oscillator TOsc. With relay 1HDR energized by current of reverse polarity after vehicle V leaves section 1T, lamp R of signal 1S will be extinguished, and lamp Y of this signal will now be lighted by a circuit passing from terminal B, through the front point of contact 31 of relay 1HDR, contact 32 of relay 1HDR closed in the reverse position, and lamp Y of signal 1S to terminal N.

When vehicle V enters section 3T, relay 3TR will become deenergized, causing relays 4aHDR and 3TPSR to in turn also become deenergized. With relay 4aHDR deenergized, green lamp G of the arm 4a of signal 4S will be extinguished and red lamp R of this signal arm will again be lighted by its circuit previously traced.

When vehicle V leaves section 2T, relay 2HDR will still remain deenergized on account of relay 3TR being deenergized. With relay 2HDR deenergized, relay 2NR will be retained in the energized position, and therefore route indicator NK will remain energized, and red lamp R of signal 2S will remain extinguished as long as relay 2AER remains energized because of section 1T being unoccupied.

When vehicle V enters section 4aT, relay 4aTR will become deenergized, so that the circuit for

relay $4a$ HDR will now be open at contact 16 of relay $4a$ TR as well as at contact 75 of relay 3TR.

When vehicle V leaves section 3T, relay $4a$ HDR will remain deenergized on account of contact 76 of relay $4a$ TR being open. Relay 2HDR will, however, now again be energized by current of reverse polarity in its circuit previously traced. With relay 2HDR energized, relay 1HDR will again become energized by current of normal polarity in the circuit previously traced, causing yellow lamp Y of signal 1S to be extinguished and green lamp G of signal 1S to again be lighted by the circuit previously traced. Relay 2HDR, upon becoming energized, opens its contact 43 at the back point, thereby deenergizing relay 2NR. The operator of a following train could therefore now effect energization of relay 2RR for causing operation of switch W to the second or reverse extreme position, if he so desired. With relay 2NR deenergized, relay 3NR will remain deenergized.

When vehicle V enters section 5T, relay 5TR will become deenergized, so that its pole-changing contacts 71 and 77 will become closed at their back points.

When vehicle V leaves section 4aT, relay $4a$ HDR will still remain deenergized on account of relay 3TPSR being deenergized.

When vehicle V leaves section 5T, relay 5TR will again become energized, so that all parts of the apparatus will then again be in the normal position.

I shall next assume that, with all parts again in the normal condition, a train or other vehicle, equipped as shown for vehicle V, arrives on portion OT of the stretch of railway track, and that the engineman or operator pushes the controller P in to close its contacts 47 and 53, and rotates it to close contact r.

When the train now enters section 1T, the wayside oscillator TOsc will become energized, as previously described, causing the train-carried receiver VRec and, in turn, relays AUR and AUSR to also become energized. Relay AUR, upon again becoming deenergized, as previously described, will complete a second circuit for energizing the vehicle-carried oscillator VOsc, this circuit passing from terminal VE, through contact 51 of relay AUSR, contact 52 of relay AUR, contact 53 of controller P, contact r of controller P, and oscillator VOsc to terminal VN. Current of the third given character will therefore now be induced in the rails of track section 1T by transmitting coils 1i and 2i.

In response to current of the third given character in the rails of section 1T, the wayside receiver TRec will energize relay RUR. Relay RUR will thereupon complete a circuit for energizing relay 2RR, this circuit passing from terminal B, through the front point of contact 54 of relay RUR, contact 78 of relay NUR, contact 80 of relay 2NR, winding of relay 2RR, and contact 58 of relay 2AESR to terminal N. Relay 2RR will then complete its stick circuit which is the same as the pickup circuit just traced except that it includes contact 79 of relay 2RR instead of the front point of contact 54 of relay RUR and contact 78 of relay NUR.

When relay 2RR becomes energized, route indicator RK becomes energized by a circuit passing from terminal B, through contact 81 of relay 2RR, and route indicator RK to terminal N. The engineman will then know that a route is being prepared over switch 3W in the reverse position.

With relay 2RR energized, relay 3RR will be energized by a circuit passing from terminal B, through contact 60 of relay 2HDR, back point of contact 61 of relay 2NR, contact 82 of relay 2RR, contact 83 of relay 3NR, and the winding of relay 3RR to terminal N.

With the relay 3RR energized, relay 3TPSR will now be energized by a second pickup circuit, passing from terminal B, through contact 68 of relay 3RR, contact 70 of relay 3TR, and the winding of relay 3TPSR to terminal N. Also, with relay 3RR energized, relay 3NRWR will be energized by current of reverse polarity in a circuit passing from terminal B, through the front point of contact 64 of relay 3RR, contact 66 of relay 3NR, and the left-hand portion of the winding of relay 3NRWR, as shown in the drawing, to terminal N.

Relay 3WR will then become energized by current of reverse polarity in a circuit which is the same as the circuit previously traced for this relay except that it includes contacts 15 and 16 of relay 3NRWR in their reverse positions instead of in their normal positions. With relay 3WR energized by current of reverse polarity, the mechanism 3WM will become energized by a circuit passing from terminal B, through contact 84 of relay 3WR in its reverse position, and mechanism 3WM to terminal N. Mechanism 3WM will therefore move switch 3W to the reverse position for preparing a route which includes section 4bT. With contact 11 of relay 3WR closed in the reverse position, relay 3NWCR will be deenergized and relay 3RWCR will become energized, when switch 3W reaches its reverse position, by a circuit passing from terminal B, through contact 11 of relay 3WR in its reverse position, contact 12 of switch 3W closed in the reverse position of switch 3W, and the winding of relay 3RWCR to terminal N.

Relay 4bHDR will now be energized by current of normal polarity in a circuit passing from terminal B, through the front point of contact 85 of relay 6TR, contacts 86, 87, 88, and 89 of relays 4bTR, 3TR, 3RWCR, and 4aHDR, respectively, the winding of relay 4bHDR, contact 90 of relay 3TPSR, and the front point of contact 91 of relay 6TR to terminal N. With relay 4bHDR energized by current of normal polarity, the red lamp R of arm 4b of signal 4S will be extinguished, and lamp G of arm 4b will be lighted by a circuit which is similar to the circuit previously traced for lamp G of arm 4a of signal 4S.

With relay 4bHDR energized, relay 2HDR will become energized by current of normal polarity in a circuit which is similar to the circuit previously traced for energizing this relay by current of normal polarity except that it includes the front points of contacts 20 and 22 of relay 4bHDR and the back points of contacts 19 and 23 of relay 4aHDR instead of the front points of contacts 19 and 23 of relay 4aHDR and the back points of contacts 20 and 22 of relay 4bHDR. Green lamp G of signal 2S will therefore again be lighted, as previously described.

I shall next assume that the train proceeds onto section 2T, and then leaves section 1T. I shall assume further that, while the train is on section 2T, a second train, equipped as shown for vehicle V, arrives on portion OT of the track, and that the operator of the second train desires to follow the first train over switch 3W in the reverse position. As long as the first train

occupies section 2T or section 3T, relay 2HDR will be deenergized, and therefore relay 2RR will be retained energized by its stick circuit, and route indicator RK will remain energized. The second train can therefore pass signal 2S, although signal 2S is indicating stop, because route indicator RK is energized.

If the operator of the second vehicle desires to move over switch 3W in the normal position, he will push the circuit controller P in while his train is still on portion OT of the track, and will leave it in the n position, before entering section 1T. After the first train has left section 1T, signal 1S will display the caution proceed indication, as previously described, and therefore the second train can enter section 1T. The wayside oscillator TOsc, the vehicle-carried received VRec, relays AUR and AUSR, the vehicle-carried oscillator VOsc, and relay NUR will then all again become energized, as previously described. As long as the first train or vehicle remains on section 2T or section 3T, relay 2RR will be retained energized, so that relay 2NR cannot become energized for effecting operation of switch 3W to the normal position.

As soon as the first train leaves section 3T, while the second train is at any point on section 1T, the control of switch 3W by the second train will become effective. It is not necessary for the second train to be at any particular point on section 1T when the first train leaves section 3T. If the first train has not left section 3T when the second train arrives at signal 2S, route indicator RK will still be energized, and therefore the second train will wait at signal 2S until the first train leaves section 3T. When the first train leaves section 3T, relay 2HDR will again become energized by current of reverse polarity, as previously described, and will cause relay 2RR to become deenergized. Relay 2AESR will then again become energized, and relay 2NR will become energized by its pickup circuit previously traced.

It follows that another advantage of my invention over previous schemes in which the control of the switch must be effected while a railway engine or other vehicle is at a given particular point such, for example, as at the location of a trackway inductor, is that, with apparatus embodying my invention, as shown in the accompanying drawings, a second train can enter section 1T while a preceding train is on section 2T or on section 3T, and the control of the switch by the second train will become effective as soon as the preceding train leaves section 3T while the second train is at any point on section 1T.

Still another advantage of my invention is that it requires less line circuit material than previous arrangements. If a trackway inductor or contact element were located at the entrance end of section 1T adjacent signal 1S, where, with apparatus embodying my invention, the control of switch 3W by an approaching train becomes effective when there is no preceding train on section 2T or section 3T, additional line circuit material would be required, including additional line wires between the entrance end of section 1T and signal 2S.

Although I have herein shown and described only one form of apparatus embodying my invention, it is understood that various changes and modifications may be made therein within the scope of the appended claims, without departing from the spirit and scope of my invention.

Having thus described my invention, what I claim is:

1. A railway traffic route control system comprising in combination, receiving means carried on a train responsive to energy of a first given character in the rails of a track which is occupied by said train, means for supplying energy of said first given character to said track, transmitting means carried on said train controlled in part by said receiving means for supplying energy of a second or a third given character to the rails of said track, receiving apparatus responsive to energy of said second or said third given character received from the rails of said track, and means controlled by said receiving apparatus upon responding to said energy of said second or said third given character for preparing a first or a second railway traffic route respectively.
2. A railway traffic route control system comprising in combination, receiving means carried on a railway vehicle responsive to energy of a first given character in the rails of a track which is occupied by said vehicle, means for supplying energy of said first given character to the rails of said track, transmitting means carried on said vehicle controlled in part by said receiving means for supplying energy of a second or a third given character to the rails of said track, receiving apparatus responsive to energy of said second or said third given character received from the rails of said track, and means controlled by said receiving apparatus upon responding to said energy of said second or said third given character for effecting operation of a railway track switch to a normal or a reverse position respectively for preparing a first or a second railway traffic route respectively.
3. A railway traffic route control system comprising in combination, receiving means carried on a railway vehicle responsive to energy of a first given character in the rails of a track section which is occupied by said vehicle, means responsive to occupancy of said track section by said vehicle for supplying energy of said first given character to the rails of said section, transmitting means carried on said vehicle controlled in part by said receiving means for supplying energy of a second given character to the rails of said section, and receiving apparatus responsive to energy of said second given character in the rails of said section for effecting operation of a railway track switch for preparing a given railway traffic route.
4. A railway traffic route control system comprising in combination, receiving means carried on a railway vehicle responsive to energy of a first given character in the rails of a track section which is occupied by said vehicle, means responsive to occupancy of said track section by said vehicle for supplying energy of said first given character to the rails of said section, transmitting means carried on said vehicle controlled in part by said receiving means for inductively supplying energy of a second given character to the rails of said section, and receiving apparatus responsive to energy of said second given character in the rails of said section for effecting operation of a railway track switch for preparing a given railway traffic route.
5. In combination, a stretch of railway track including a switch and divided into an approach section and a detector section adjacent said switch, manually operable means carried on a

railway vehicle, a first and a second route control relay, means controlled by a first or a second operation of said manually operable means and by said vehicle on said approach section for energizing said first or said second route control relay respectively, a third and a fourth route control relay, an approach stick relay, a pickup circuit for energizing said approach stick relay in response to a railway vehicle occupying said approach section if said third and fourth route control relays are deenergized, a stick circuit controlled by a vehicle occupying said approach section for retaining said approach stick relay energized, a pickup circuit for each of said third and fourth route control relays controlled by said approach stick relay and by front contacts of said first and second route control relays respectively, a stick circuit for each of said third and fourth route control relays controlled by a back contact of the other and by a front contact of said approach stick relay, a second stick circuit for each of said third and fourth route control relays controlled by a back contact of the other and by a vehicle on said detector section, and means controlled by a front contact of said third or said fourth route control relay if said detector section is unoccupied for effecting operation of said switch to a first or a second position for preparing a first or a second traffic route respectively.

6. In combination, a stretch of railway track including a switch, a home signal for governing traffic movements over said switch capable of displaying a stop indication and capable of displaying a first indication when said switch is in a first position for preparing a first traffic route and also capable of displaying a second indication when said switch is in a second position for preparing a second traffic route, a distant signal for governing traffic movements on said track approaching said home signal in the direction of traffic movements governed by said home signal, said distant signal capable of displaying a clear proceed indication when said home signal is displaying either said first or said second indication and also capable of displaying a stop indication, a first route indicator adjacent said distant signal capable of being energized when said switch is controlled to occupy said first position, a second route indicator adjacent said distant signal capable of being energized when said switch is controlled to occupy said second position, an approach track section for said distant signal, transmitting means carried on a train, manually operable means on said train capable of controlling said transmitting means to energize the rails of said approach section by current of one or another given character when said train occupies said approach section, means controlled by current of said one given character in said approach section for effecting operation of said switch to said first position and controlling said home signal to display said first indication and also controlling said distant signal to display said clear proceed indication and effecting energization of said first route indicator, means controlled by current of said another given character in said approach section for effecting operation of said switch to said second position and controlling said home signal to display said second indication and also controlling said distant signal to display said clear proceed indication and effecting energization of said second route indicator, and traffic responsive means for controlling said home and distant signals to display the stop indication when a train passes said home and distant signals respectively.

7. A railway traffic route control system comprising in combination, a stretch of railway track including a switch and an approach section, receiving means carried on a railway vehicle responsive to current of a first given character in the rails of said approach section when said railway vehicle occupies said approach section, means controlled by said vehicle upon entering said approach section for supplying current of said first given character to the rails of said approach section, a receiving relay controlled by said receiving means, a push-turn circuit controller on said vehicle, a receiving stick relay having a pickup circuit controlled by said receiving relay and having a stick circuit controlled by a front contact of said push-turn circuit controller, means controlled by a front contact of said receiving stick relay and by a back contact of said receiving relay and also by a front contact and by a normal or a reverse contact of said push-turn circuit controller for inductively supplying current of a second or a third given character respectively to the rails of said approach section, and means controlled by said current of said second or third given character in said approach section for effecting operation of said switch for preparing a first or a second railway traffic route respectively.

8. A railway traffic route control system comprising in combination, a stretch of railway track including a switch and an approach section, receiving means carried on a railway vehicle responsive to current of a first given character in the rails of said approach section when said railway vehicle occupies said approach section, means controlled by said vehicle upon entering said approach section for supplying current of said first given character to the rails of said approach section, a receiving relay controlled by said receiving means, a push-turn circuit controller on said vehicle, a receiving stick relay having a pickup circuit controlled by said receiving relay and having a stick circuit controlled by a front contact of said push-turn circuit controller, means controlled by a front contact of said receiving stick relay and by a back contact of said receiving stick relay and also by a front contact and by a normal or a reverse contact of said push-turn circuit controller for inductively supplying current of a second or a third given character respectively to the rails of said approach section, a slow release whistle control valve magnet controlled by a back contact of said receiving stick relay in multiple with a front contact of said receiving relay, and means controlled by said current of said second or third given character in said approach section for effecting operation of said switch for preparing a first or a second railway traffic route respectively.
